UNITED STATES PATENT OFFICE.

JOSEPH H. AMES, OF ST. LOUIS, MISSOURI, ASSIGNOR TO AMERICAN CAR & FOUNDRY COMPANY, OF ST. LOUIS, MISSOURI, A CORPORATION OF NEW JERSEY.

ERECTING-CRANE.

SPECIFICATION forming part of Letters Patent No. 728,825, dated May 26, 1903.

Application filed July 21, 1902. Serial No. 116,400. (No model.)

To all whom it may concern:

Be it known that I, JOSEPH H. AMES, a citizen of the United States, residing at St. Louis, Missouri, have invented a certain new and useful Improvement in Erecting-Cranes, of which the following is a full, clear, and exact description, such as will enable others skilled in the art to which it appertains to make and use the same, reference being had to the accompanying drawings, forming part of this specification, in which—

Figure 1 is a side elevational view of my improved crane. Fig. 2 is a front elevational view of the same. Fig. 3 is an enlarged elevational view of one of the trolleys. Fig. 4 is a detail view hereinafter described.

This invention relates to a new and useful improvement in electric cranes designed especially for use in the erection of steel rail-way-cars, the object being to enable said crane to handle the different parts of the car or the riveting-machines that work on the car to advantage.

The crane shown in the drawings is mounted upon a truck or platform designed to be operated over a track, the gage of which track is made as wide as possible, so that the wheels on the side opposite the masts will bear on the rail and oppose the tendency of the structure to overturn by reason of the long overhang of the jibs. There are two masts extending upwardly from the truck, from which project stationary jibs or beams in a horizontal direction. These jibs carry a traveling bridge-crane of the ordinary type. The truck is provided with an electric motor, which is geared to one of its axles, whereby the entire structure may be moved along the track in either direction at the will of the operator. Counterbalance-weights are placed on the truck between the masts to counteract the tendency of the structure to overturn by reason of the weight of the crane-bridge and its load when at the extreme outer end of the jibs. On the upper faces of the jibs are suitable rails on which the wheels of the movable bridge run. This bridge is of the ordinary crane type, and the movement in this case is effected by a pendent hand-chain passing over a sprocket-wheel which in turn is located

on a shaft running the full length of the bridge, and the movement of this shaft, by pulling on the chain, is communicated to the truck-wheels of the bridge by means of a suitable pinion and gear-wheel on the truck-wheel 55 axle. Upon the traveling bridge-crane are mounted two trolleys, each being equipped with an electric motor and a drum for reeling up the wire rope by means of which the load—such, for instance, as a hydraulic or pneumatic riveter—is hoisted, the power of the motor being communicated to said drum through a suitable train of gears. The motor is operated by a suitable controller, which is operated from the floor by means of pendent hand-chains.

The bridge-crane is so constructed that one end extends beyond and overhangs one of the jibs in order to permit the placing thereon of a relatively stationary motor-driven hoisting-drum without interfering with the travel of the movable trolleys. This hoisting-drum is designed to reel up two independent wire ropes, which leave the drum in a horizontal plane, pass over sheaves which are attached 75 to the side of the bridge-crane, one being near each end, and thence in a vertical plane toward the floor. The function of this hoist is to enable the operator to attach the ropes to parts of the car or other structure which may 80 be lying on the floor and which he desires to lift, move to the desired position, and hold securely while the necessary bolting is done preparatory to the riveting operation. The motor of this hoist is operated through a controller having pendent hand-chains similar 85 to those on the trolley.

The conductors supplying electric current to the crane are preferably located between the rails on which the crane runs, and the 90 collector is attached to the bottom of the truck and extends downward to make contact with the conductors in a manner similar to the well-known "third-rail" system for electric railways. The hydraulic or pneumatic power for the riveting-machines may be conveyed to same by means of swivel-jointed piping or hose.

With these objects in view my invention consists in the construction, arrangement, and 100

combination of the several parts, all as will hereinafter be described, and afterward pointed out in the claims.

In the drawings, 1 indicates the track-rails, 5 upon which is mounted the truck-base 2. This truck-base is so constructed that counterbalance-weights 2^a may be carried thereon.

3 indicates a motor mounted on the truck-base, which is geared by a train of gearing 4 to one of the wheel-axles, whereby the entire crane may be caused to travel in either direction on its track at the will of the operator.

5 indicates jaws secured to the truck-base and extending down on each side of the outer

15 rail to anchor the truck to the floor and prevent its overturning in the event that the counterbalancing-weights carried thereby are insufficient to hold the same in the desired position.

20 6 indicates masts rising from each end of the truck-base and suitably strengthened by lattice-bars. These masts carry at their upper ends overhanging jibs 7, upon whose upper faces are arranged track-rails 8. These

25 track-rails support the bridge-crane. This bridge-crane is in the form of a truck 9, having wheels 10 operating upon the track-rails 8.

11 and 12 are the hoisting devices arranged upon the bridge crane or truck 9, said devices

30 being in the form of trolleys, and each, as is usual in electric hoisting apparatus, having a controller 11^a, which is manipulated by means of the pendent hand-chains 13. The hoisting-drums 12^a, driven by the motors 13^a, 35 operate ropes 14, which carry the tackle-blocks 15, said tackle-blocks being provided with hooks for connection with riveting or other machinery suspended therefrom.

16 indicates hand-ropes for causing the trolley to move independently along the bridge 9.

40 17 indicates the hand rope or chain suspended from each trolley, which rope or chain passes over a sprocket-wheel on the shaft 18, as best shown in Fig. 3, said shaft being connected, through the pinion 18^a and gear-wheel 18^b with the pinion 10^a on the shaft, with the wheels 10, whereby said wheels are driven and the truck 9 and its associate parts may be caused to travel at the will of the operator 45 over the jibs 7. The said sprocket-wheel may be suitably supported from the trolley-frame, and said wheels work on a feather on said shaft 18, or the shaft may be angular in cross-section, as shown, so that irrespective of the 50 position of either trolley on the bridge the chains for causing movement of the bridge-crane are within the reach of the operator.

55 In Fig. 4 a motor X, controlled through the hand-chains 17^a and controller 17^b, takes the place of the sprocket-wheel and said hand-rope 17, and upon manipulating the hand-chains 17^a the current to said motor is turned on, thus energizing said motor, and through the gears 18^a, 18^b, and 10^a driving the wheels 60 10, therein shown.

65 As shown in Fig. 2, one end of the truck is

projected longitudinally thereof outwardly, so as to overhang the jib laterally of said jib, said outwardly-projecting end of truck 9 being indicated at 19. This projecting end of 70 truck 9 is provided with a motor-driven hoisting-drum designed to be manipulated by pendent hand-ropes 20 for controlling the operation of the same. The drum referred to, which is driven by this "auxiliary hoisting mechanism," as it might be called, is designed to wind or unwind two ropes 21 and 22, said ropes leaving the drum in a horizontal direction and passing over sheaves or pulleys 23 and 24, mounted upon the truck 9.

80 From the foregoing it will be seen that from each "trolley," as the hoisting devices 11 and 12 are commonly termed, hang three sets of hand-chains—one, 17, for bridge travel, another, 16, for trolley travel, and the other, 13,

85 for controlling the motor and the rotation of the hoisting-drum. This enables the operator of the riveting-machine to place his dies

90 on any rivet or to move from one rivet to another in the shortest possible time. These three movements, combined with the movement of the entire structure along the track on the floor of the shop, enable the operator

95 to move from one end of a car, or whatever structure may be under construction, to the other regardless of its length or to move from one car to another or one structure to another, as may be desired. The purpose of

100 having two trolleys on the bridge is to permit the employment of different sizes of riveting-machines in the same structure, thus obviating lost time resulting from changing machines and their connections where it is desirable to use machines of different sizes

105 or different machines for different kinds of work. Each trolley being entirely complete

110 in itself and independent of the other enables two operators to operate different riveting-machines on the same structure at the same time, assuming, of course, that the bridge is initially set in proper position. By

115 referring to Figs. 1 and 2 it will be observed that the entire structure is comparatively light, the masts and jibs being braced and tied by the employment of appropriately arranged and disposed lattice or angle and tie bars 6^b, and the jibs and masts are provided

120 with suitable braces 6^a for bracing said jibs and tying the same to the masts.

125 It is obvious that instead of employing the hand-chains for effecting the bridge and trolley travel motors could be employed with appropriate gearing, whereby by operating a switch on the truck said motors could be cut in circuit, respectively, to effect such travel.

130 I am aware that many minor changes in the construction, arrangement, and combination of the several parts of my device can be made and substituted for those herein shown and described without in the least departing from the nature and principle of my invention.

Having thus described my invention, what

I claim as new, and desire to secure by Letters Patent, is—

1. In an erecting-crane, the combination with a truck having a receptacle for counter-balancing-weights, masts rising therefrom, jibs supported by said masts and projecting therebeyond, and jaws connected from the opposite side of said truck, adapted to co-operate in anchoring said truck; substantially as described.

2. In an apparatus of the character described, the combination with a truck having masts at each end, jibs extending at the upper ends of said masts, connections between said masts and jibs for bracing and tying the same, and a bridge-crane mounted on said jibs; substantially as described.

3. In an apparatus of the character described, the combination with masts and jibs, of brace and tie bars for rigidly securing said parts together, a bridge mounted to traverse said jibs, and a plurality of trolleys on said bridge; substantially as described.

4. In an apparatus of the character described, the combination with a movable bridge, of independently-movable trolleys arranged thereon, and means identified with each trolley for controlling the movement of said bridge irrespective of the position of the trolleys thereon; substantially as described.

5. In an apparatus of the character described, the combination with a traveling bridge, of trolleys mounted thereon and capable of movement in a direction at right angles to the movement of the bridge, means for moving each trolley independently of the other, and means carried by each trolley, irrespective of its position on the bridge, for effecting the movement of said bridge; substantially as described.

6. In an apparatus of the character described, the combination with two jibs, a bridge mounted to travel thereon, a trolley arranged on the bridge between the jibs, and hoisting apparatus arranged on one end of said bridge outside of said jibs; substantially as described.

7. In an apparatus of the character described, the combination with a traveling bridge, one end of which extends longitudinally outwardly to form an overhang laterally of the jibs, and a hoisting apparatus ar-

ranged on said outwardly-projecting end; substantially as described.

8. In an apparatus of the character described, the combination with two jibs, a traveling bridge mounted thereon and having an overhanging end, hoisting apparatus on said bridge and hoisting-ropes controlled by said hoisting apparatus, said ropes extending inwardly and depending from the bridge at points between the jibs; substantially as described.

9. In an apparatus of the character described, the combination with a traveling bridge, of independently-movable trolleys arranged thereon, and an auxiliary hoisting apparatus arranged on said bridge beyond the limit of travel of said trolleys; substantially as described.

10. In an apparatus of the character described, the combination with two jibs, a bridge mounted to travel thereon, a movable trolley arranged to travel on said bridge, means carried by said trolley for effecting the movement of said bridge irrespective of the position of the trolley thereon, an auxiliary hoisting mechanism arranged on the bridge beyond the limit of travel of said trolley, and ropes operated by said auxiliary hoisting mechanism which ropes depend from the bridge at points between the jibs; substantially as described.

11. In an apparatus of the character described, the combination with a movable truck, carrying two masts, of overhanging jibs extending from said masts, a bridge designed to travel upon said jibs, independently-movable trolleys mounted to travel upon said bridge, means for effecting the independent movement of said trolleys, means for independently controlling the operation of the hoisting-drum carried by said trolleys, and means carried by each of said trolleys for effecting the travel of said bridge; substantially as described.

In testimony whereof I hereunto affix my signature, in the presence of two witnesses, this 18th day of July, 1902.

JOSEPH H. AMES.
